UNITED STATES PATENT OFFICE

AXEL M. WALSTROM, OF MINNEAPOLIS, MINNESOTA, ASSIGNOR TO ELGIN BUTTER TUB COMPANY, OF ELGIN, ILLINOIS, A CORPORATION OF ILLINOIS

COVER AND PROCESS OF MAKING

Application filed April 14, 1927. Serial No. 183,691.

This invention relates to a container such as a container made of wood or other suitable material and particularly to a cover for said container. While the container of the type referred to may be used for various purposes, one purpose for which the container has been used is to contain butter. Such containers are commonly of cylindrical form and preferably somewhat tapered toward their bottom or lower end.

It is desirable to have such a container of simple, strong and rugged construction and to have the same of neat and uniform appearance. It is also desirable to have such a container and the cover therefor constructed and arranged so that there are no projecting parts adapted to injure the hands of the persons handling the container or cover. It is further desirable to have such a container and cover therefor so constructed that if the containers are piled one on another, and moved in engagement with each other, that the cover or parts thereof will not be damaged or separated in any manner. It is desirable to have the covers of such form that they may be nested or packed in very compact form for handling and transportation.

It is an object of this invention, therefore, to provide a cover for a container preferably of cylindrical form, having a crowned top surface and a beveled peripheral edge.

It is another object of the invention to provide a cover for a container preferably of cylindrical form, having a central portion of wood or similar material and having a metal flange rolled thereon so that it grips the edge thereof.

It is still another object of the invention to provide a cover for a container preferably of cylindrical form, having a central portion of wood or similar material and having a metal flange surrounding the edge thereof, said flange being secured to said central portion without the use of nails or other separate fastening means, by being rolled or spun into engagement with the edge of said central portion which is made of angular or irregular form in radial cross section.

It is still further an object of the invention to provide a cover for a container prefer-

ably of cylindrical form, having a central portion with the edge thereof beveled in opposite directions and having a metallic rim or flange fitted or clamped thereto, extending about both beveled portions of said edge.

It is still another object of the invention to provide a cover for a container preferably of cylindrical form, said cover having a central portion of wood or other material surrounded by a metallic flange, said flange having circumferentially extending corrugations therein and flaring outwardly from the lower side of said cover.

It is also an object of the invention to provide a novel and efficient method of making a cover for a container preferably of cylindrical form.

These and other objects and advantages of the invention will be fully set forth in the following description made in connection with the accompanying drawings, in which like reference characters refer to similar parts throughout the several views and in which:

Fig. 1 is a view in side elevation of a container with the cover thereon;

Fig. 2 is a partial view in side elevation of the container, portions thereof and of the cover being broken away and other parts being shown in vertical section;

Fig. 3 is a radial section through the metal rim before being applied to the cover;

Fig. 4 is a radial section of the edge portion of the central part of the cover before having the surrounding metal frame or flange applied;

Fig. 5 is a view in radial section of a central part of the cover and flange, showing how the flange is first applied to the cover; and

Fig. 6 is a view showing portions of several completed covers as they may be assembled in nested relation.

Referring to the drawings, a container is shown, and while the container may have various forms, in the embodiment of the invention illustrated it is shown as cylindrical in form and tapered somewhat toward its lower end. Such a container is now largely used as a tub in which to pack and transport butter, lard and other similar materials.

Said container is equipped with a plurality of hoops 11 closely fitting thereon and while any suitable type of hoop may be used, one form which is preferred in practice is that shown and described in applicant's prior Patent No. 1,605,628, granted Nov. 2, 1926, for "metal hoops". The container 10 is shown as having the top portion 10^a slightly beveled inwardly. While this beveled portion is not absolutely necessary, it preferably is used with the novel cover to be later described.

The cover for the container 10, designated generally as 12, comprises a central portion 12^a of disk-like form, and while in practice it has been found convenient to make the tub 10 and cover portion 12^a of wood, it is apparent that said parts can be made of composition board or other similar material. The cover portion 12^a may be made of one or more pieces as found desirable, and when used with a cylindrical container, is circular in shape. The peripheral edge of said portion 12^a is then made of angular shape in cross section and while said edge may be of various conformations, in the embodiment of the invention illustrated it is made generally convex or with an outwardly directed angle. Said portion 12^a has its top side beveled outwardly and downwardly to form a surface 12^b and said portion is also further beveled at the under side of its edge to form a surface 12^c. While the surfaces 12^b and 12^c may be of various contours and inclined at various angles, in the embodiment of the invention illustrated they are shown as substantially conical surfaces, beveled respectively substantially at angles of 30° and 45° to the top surface of portion 12^a. While the surfaces 12^b and 12^c may meet at a sharp angle, preferably there is a quite narrow cylindrical portion 12^k therebetween.

A rim or flange portion 12^d is provided for the cover 12 which is made from a flat strip of thin metal which strip is rolled in a suitable machine comprising properly corrugating rolls, to the shape shown in Fig. 3. Said flange has an intermediate bead 12^e formed therein from the sides of which extend the flange portions 12^f and 12^g. It will be seen that the flange portions 12^f and 12^g flare outwardly from the sides of the bead 12^e. The flange 12^g is further provided with a terminal corrugation or bead 12^h illustrated as substantially semi-cylindrical in form and having its concave side directed inwardly of the rim or oppositely to that of bead 12^e.

The flange 12^d is cut to proper length and then bent into cylindrical shape, the ends thereof being connected by the rivets 13 to form a cylindrical hoop. After the hoop has been thus riveted and formed, the same is placed about the portion 12^a, one side of the bead 12^e being placed against the surface 12^c as shown in Fig. 5 and the meeting edge 65 of the surface 12^c and 12^b being disposed in

the corner between the side of the bead 12^e and the flange 12^f. The portion 12^a and the rim 12^d are then brought to a machine having a rotating spinning roller 14 thereon. The flange 12^f is brought into contact with said roller 14 and said roller then rolls said flange down onto the surface 12^b as shown in Fig. 2. The portion 12^a and the rim 12^d are rotated relatively to the roller 14 and the flange 12^f is thus rolled or spun down onto the surface 12^b about the entire periphery of the portion 12^a, the bead 12^e being thus brought into close engagement with the surface 12^c, the rim clamping the edge of the central portion 12^a. The rim engages the surfaces at both sides of the angle appearing in the radial cross section of the edge of said central portion so that it is tightly crimped thereto and is thus fixed in position relatively to said cover. After the rim is thus rolled onto the central portion 12^a it is very firmly held thereon and tightly secured to the portion 12^a without the use of any nails or separate fastening means. The edge of the rim 12^d is rolled into very close contact with the surface 12^b and may even be rolled somewhat into said surface so that there is a substantially smooth and continuous surface along the top of flange 12^f and surface 12^b. After the rim 12^d has been thus rolled onto the cover, the cover presents the appearance shown in Figs. 1, 2, and 6. As above stated, the portion projecting from the bottom side of the cover flares outwardly. It will be seen that the portions 12^f and 12^g fit tightly about the angular portion of the edge of the central portion 12^a which is formed by surfaces 12^b and 12^c. The metal rim, of course, bends in a curve and it, as well as the edge of the central portion, is broadly convex. It will be also noted that the side of the bead 12^e not in engagement with the cover is disposed in a plane substantially aligned with the plane of the bottom side of the cover. The cover can now be placed on the container 10 and the flange 12^d extends down about the top of the portion 10^a. It will be seen that the side of the bead 12^e which is not in engagement with the central portion 12^a of the cover is disposed substantially at the top of the container 10. The projecting flange on the cover extends down over the top of the tub 10 and forms a novel and effective closure therefor.

From the above description it is seen that applicant has provided a very simple and efficient cover for a container such as the well known butter tub. The device is very rugged and durable and is comparatively easily and inexpensively made. The device is very neat and ornamental in appearance. There are no parts of the cover projecting which might injure the hands of the person handling the article and there are no fasteners which might protrude and catch on the hands or other ob-

jects. The beaded form of the rim cover makes the same quite strong. It is also pointed out that with such a cover a narrower strip of stock for the member 12^d can be used than where a rim is used extending along the periphery of the cover and over the top, such as have been used in some covers of the prior art. The covers also lend themselves to being packed or nested in compact form such as shown in Fig. 6, so that the transportation cost can be kept at a low figure. The containers are often piled one on another with the covers thereon and it is a common practice to slide one container from another and across the top thereof. If there are fastenings in the top of the cover or if the edge of the rim projects above the top of the cover the same is quite apt to be torn loose as one heavy tub slides across the other. With the present construction there is no danger of any such occurrence as the rim is entirely below the top of the cover. The cover has been amply demonstrated in actual practice and found to be very successful and efficient.

It will, of course, be understood that various changes may be made in the form, details, arrangement and proportions of the apparatus and in the steps and sequence of steps of the method, without departing from the scope of applicant's invention, which, generally stated, consists in a method and apparatus capable of carrying out the objects above set forth, such as disclosed and defined in the appended claims.

What is claimed is:

1. A cover for a cylindrical container comprising a non-metallic central portion having its top beveled downwardly adjacent its edge for an appreciable distance to form an annular zone and a metallic rim spun about the edge of said central portion and extending partially across said zone.

2. A cover for a container comprising a non-metallic central portion with a peripheral edge formed substantially as an angle in radial cross section, a peripheral rim secured to said central portion pressed into engagement with said peripheral edge at both sides of said angle and having its upper edge disposed below the top of said central portion whereby a cover is formed free of any fastening means driven into the body of said central portion.

3. The method of forming a cover for a container which consists in providing a non-metallic central portion, rolling a rim from a strip of flat metal to form a longitudinally extending corrugation therein, bending said strip and uniting the ends thereof to form a hoop and spinning said hoop about the edge of said central portion.

4. The method of forming a cover for a container which consists in providing a non-metallic central portion, forming an angular edge on said central portion, rolling

a rim from a strip of flat material to form a longitudinally extending corrugation therein, bending said strip and uniting the ends thereof to form a hoop and spinning said hoop onto the edge of said central portion to embrace the edge surface thereof with its upper edge below the top of said central portion.

5. The method of forming a cover for a container which consists in providing a central non-metallic portion, forming the edge portion of the top surface thereof with a downwardly inclining surface, forming an inwardly inclining surface at the periphery of said cover intersecting said downwardly inclining surface in a circumferential line, to form an outwardly directed angle in radial cross section, rolling a rim from a strip of metal to form a corrugation extending longitudinally thereof, bending said strip and uniting the ends thereof to form a hoop of frusto-conical form, bringing one side of said corrugation against one side of the angle at the edge of said central portion and rolling said hoop about the edge of said central portion whereby it is secured thereto and extends partly over said downwardly inclined portion.

6. The method of forming a cover for a container which consists in providing a non-metallic central portion forming the edge thereof of convex shape in radial cross section, forming a hoop of a strip of metal and spinning said hoop about the edge of said central portion so as to embrace the same and be secured thereto with its upper edge below the top of said central portion.

7. A cover for an open top container comprising a non-metallic disk-like central portion having its top edge beveled downwardly adjacent its edge for an appreciable distance, a metallic rim clamped about the edge of said central portion and extending partially across said beveled portion, said rim extending inwardly of the outer edge of said central portion below said beveled portion and having a depending downwardly flaring flange below said central portion, said flange having a bead at the lower edge of its concave side directed inwardly, whereby said covers may be arranged in nested relation.

8. A metal bound cover for a container, which cover has a central disk-like non-metallic portion having a crowned upper surface, a metal binding fitting about the edge of said non-metallic portion and closely engaging the same and having its inner edge extending inwardly for some distance on said upper surface but disposed below the uppermost portion of said upper surface and rolled into smooth engagement with said upper surface.

9. A cover for a container comprising a non-metallic central portion having its

peripheral edge angular in radial cross section and a metallic rim crimped on and closely engaging said peripheral edge at both sides of said angle, said central portion having an annular zone adjacent its edge disposed below the portion surrounded by said zone, the inner portion of said rim extending partially over said zone and having its inner edge rolled into close engagement with the upper surface of said non-metallic portion within said zone and below the uppermost surface of said central portion.

10. A cover for a container comprising a non-metallic central portion with a peripheral edge angular in cross section, a rim rolled onto and closely engaging said peripheral edge and depending below the bottom surface thereof, said rim having a plurality of circumferentially extending 20 corrugations therein, one of which corresponds to and closely fits said edge of said central portion.

11. A cover for a container comprising a non-metallic central portion having an angular peripheral edge, a metallic rim clamped onto said peripheral edge and closely engaging the same, said rim having a depending flange, said flange flaring downwardly whereby said covers may be assembled in nested relation.

In testimony whereof I affix my signature.
AXEL M. WALSTROM.
